(57) **CLAIM**

The ornamental design for a handset, as shown and described.

DESCRIPTION

FIG. 1 is a bottom plan view of a first embodiment of a handset showing our new design;

FIG. 2 is a right side view thereof;

FIG. 3 is a front view thereof;

FIG. 4 is a left side view thereof;

FIG. 5 is a top plan view thereof;

FIG. 6 is a rear view thereof;

FIG. 7 is a perspective front view thereof;

FIG. 8 is a perspective rear view thereof;

FIG. 9 is a front view of the handset of FIGS. 1-8 in an in-use open position;

FIG. 10 is a perspective front view of the handset of FIGS. 1-8 in an in-use open position;

FIG. 11 is a bottom plan view of a second embodiment of a handset showing our new design;

FIG. 12 is a right side view thereof;

FIG. 13 is a front view thereof;

FIG. 14 is a left side view thereof;

FIG. 15 is a top plan view thereof;

FIG. 16 is a rear view thereof;

FIG. 17 is a perspective front view thereof;

FIG. 18 is a perspective rear view thereof;

FIG. 19 is a front view of the handset of FIGS. 11-18 in an in-use open position;

FIG. 20 is a perspective view of the handset of FIGS. 11-18 in an in-use open position;

FIG. 21 is a perspective front view of a third embodiment of a handset showing our new design having interior surfaces as shown in the in-use position in FIGS. 19-20, including the key button area; and,

FIG. 22 is a front view thereof.

The third embodiment of the handset shown in FIGS. 21 and 22 has the identical bottom plan view, left side view, right side view, top plan view, and rear view of the handset shown in FIGS. 11-20.

The broken line showing of the environmental structure is for illustrative purposes only and forms no part of the claimed design.
